Primary Examiner—Dominic Simone

(74) Attorney, Agent, or Firm—Fross Zelnick Lehrman & Zissu, P.C.; Lawrence E. Apolzon, Esq.

(57) CLAIM

The ornamental design for footwear, as shown and described.

DESCRIPTION

FIG. 1 is a front perspective view of a shoe showing my footwear design;

FIG. 2 is a left side view of the footwear shown in FIG. 1;

FIG. 3 is a right side view of the footwear shown in FIG. 1;

FIG. 4 is a front view of the footwear shown in FIG. 1;

FIG. 5 is a rear view of the footwear shown in FIG. 1; and,

FIG. 6 is a top view of the footwear shown in FIG. 1.

The broken line showing of a portion of the sole, heel, and portion of the straps, is for illustrative purposes only and forms no part of the claimed design.
